Attorney

UNITED STATES PATENT OFFICE.

JOHN M. McVEY, OF LIMA, OHIO.

STOP AND WASTE COCK.

SPECIFICATION forming part of Letters Patent No. 340,807, dated April 27, 1886.

Application filed February 18, 1886. Serial No. 192,411. (No model.)

To all whom it may concern:

Be it known that I, JOHN M. McVEY, a citizen of the United States of America, residing at Lima, in the county of Allen and State of Ohio, have invented certain new and useful Improvements in Stop and Waste Cocks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in cocks for cutting off the supply of water to a building or tank and allowing the water in the supply-pipes to escape to a waste-pipe; and to this end my invention consists in a cut-off valve, the construction of which will be hereinafter fully set forth, and specifically pointed out in the claims.

20 In the accompanying drawings, which illustrate my invention, Figure 1 is a side view of a valve constructed in accordance with my invention, means for operating the same being shown in connection therewith. Fig. 2 is a vertical sectional view of a valve constructed in accordance with my invention, and Fig. 3 is 25 a plan view of one of the valves detached.

30 A refers to a suitable casing or casting, which is preferably made of a single piece, the body portion A' of said casting consisting of a cylindrical portion, A'', which is adapted to be closed by a screw-threaded cover, a, which has on its outer side a projecting portion, with which the jaws of a wrench may engage in putting the same in place or removing the same from the casing. The casing A is supported 35 on legs or uprights b, the lower ends of which are turned outwardly, so that they may be bolted to the floor or other support.

35 c refers to a projecting arm, the upper end of which is bifurcated, as shown at c', so as to 40 form side supports for the pivot, which holds the lever D in place.

45 E refers to a depending portion, which is formed integral with the casing, and is screw-threaded exteriorly on its lower end, while at 50 a suitable point within the same it is provided with a valve-seat, e, beneath which the diameter

55 of this depending portion is enlarged, so as to provide a space in which the valve may play. Opposite the depending portion E the casing A has an upwardly-projecting portion, F, formed integral therewith, and through this upwardly-projecting portion a bar or rod, G, passes. The upwardly-projecting portion F is screw-threaded, so that a cap, F', which is placed over the bar G, can be secured thereto, 60 and packing, so as to form a water-tight joint, being inserted between the upwardly-projecting portion F and the cap F'.

65 H refers to a projecting portion, which is screw-threaded exteriorly, so that the supply-pipes which distribute the water throughout the building can be attached thereto, and adjacent to this projecting portion to which the supply-pipe is attached is a similar projecting portion, I, which is, near its outer end, reduced in diameter, so as to form a valve-seat, 70 i, and to this projecting portion I the inlet or supply pipe which leads from the street-mains or from suitable tank is connected. By this construction the casing A is provided with 75 three openings through which the water may pass.

75 The bar or stem G is provided at its lower end with a valve, E', which is adapted to reciprocate within the depending portion E, and will fit snugly against the valve-seat e when the rod or stem is elevated. This stem G has also attached about its central portion a sleeve, G', which can be rigidly secured thereto, said sleeve having formed integral therewith outwardly-projecting ears g g, through which pass suitable bolts or screws for connecting thereto links K and K'. The end of the link K is slotted, as shown at k, and through said slot passes a bolt or screw, which engages with an outwardly-projecting lug, which is formed integral with the casing A. The opposite link, K', is also pivotally secured between the ears g g at one end, while its opposite end is pivotally secured to a valve, I', said valve reciprocating 95 within the enlarged portion of the tube I. The valve is of ordinary construction, and has a packing secured to the face of the same, while its edges are fluted, as shown in Fig. 3, so that a passage-way will be provided between the pipe and the valve. The end of the bar or stem G is pivotally attached to the lever D,

and said lever is provided with a weight, D', which will have a tendency to hold the stem G elevated, so that the valve E' therein will be held firmly against its seat *e*, and when held 5 in this position the valve I' will also be held away from its seat.

When the valves are in the position shown in Fig. 2, the water will enter the supply-pipes and pass into the hollow casing, and from 10 thence will flow through the distributing-pipes. When it is desired to cut off the flow of water from the distributing-pipes, the end of the lever D is elevated, thus depressing the stem G, which movement causes the valve I' 15 to abut against its seat *i*, so as to close the supply-pipe and open the valve E'. The water in the distributing-pipes will then flow through the connection H, and through the casing into the waste-pipe, thus cutting off the supply of 20 water to the building and permitting the distributing-pipes to be emptied.

L refers to a pivoted lever with teeth thereon, which is unsupported in a suitable frame, L', having side projecting pieces, *l*, between 25 which is located a sliding rack-bar, *l'*, which engages with the teeth of the lever. Said rack-bar is connected to the end of the lever by suitable connection, as shown, and by depressing the lever L the lever D will be raised, for the 30 purpose hereinbefore stated.

By providing the stem G with a link, K, an outward pressure can be communicated to the valve I' without throwing the stem G off the center, and as each of the links K K' will bind 35 against their bearings the links cannot be depressed beyond a horizontal position.

By providing the stem G with an adjustable sleeve the valves E' and L' can be adjusted so as to coact, so that when the supply-valve is moved away from its seat the cut-off valve will 40 bear firmly against its seat and prevent the water flowing through the same.

I claim—

1. A valve for the purpose set forth, a casing having a removable cap, and inwardly- 45 projecting pin formed integral with or attached to one of the sides of the casing for the reception of the slotted end of a link, said link being attached to an adjustable sleeve secured on the valve-stem, so as to limit the play 50 of said stem, in combination with the valves E' and I', substantially as shown, and for the purpose set forth.

2. A casing, A, provided interiorly with a vertical reciprocating valve-stem, G, a sleeve, 55 G', adjustably secured thereon, said sleeve having projecting ears *g*, to which are pivotally attached links K and K', one of said links being slotted and connected to the casing, while to the other is attached a sliding valve, 60 a valve, E', attached to the base of the same, the parts being combined and organized substantially as shown, and for the purpose set forth.

In testimony whereof I affix my signature in 65 presence of two witnesses.

JOHN M. McVEY.
